United States Patent Office

Des. 195,785
Patented July 30, 1963

195,785

MINERALS CONCENTRATOR

Herbert C. Brauchla, Fremont, and Paul Ruminsky,
Amherst, Ohio; said Ruminsky assignor to said
Brauchla

Filed Dec. 20, 1961, Ser. No. 67,991

Term of patent 14 years

(Cl. D55—1)

FIG. 1 is a perspective view of the front and one side of a minerals concentrator embodying our new design; FIG. 2 is a front elevational view thereof;

FIG. 3 is a top plan thereof; and

FIG. 4 is a rear elevational view thereof;

The side opposite that shown in FIG. 1 is a mirror image thereof except for the control panel.

We claim:

The ornamental design for a minerals concentrator, as shown and described.
